WRITING PEN

George S. Walter, Chicago, Ill.

Application December 12, 1934, Serial No. 757,176

12 Claims. (Cl. 120—44)

This invention relates to pens, and particularly to a type of pen, in the use of which, considerable pressure is frequently exerted on the writing end thereof, as, for example, in the use of stylographic pens which are used and are especially well adapted for making carbon copies of original writings.

One object of the present invention is to provide a construction and arrangement whereby portions of the pen are protected against scooping up dust, dirt, paper fibers and the like, which tend to clog the ink passage and seriously interfere with the efficient operation of the pen.

Another object of the invention is to provide a pen of the character described with a self-contained mechanical filler, or, in other words, a pen of the stylographic type which is capable of being conveniently filled without resorting to the old method of using a dropper or the like, and which is still employed in filling pens of the stylographic type.

Another object of the invention is to provide a stiff, non-spreading pen point capable of receiving pressures suitable for producing carbon copies.

Another object of the invention is to provide a novel form of vent for admitting air to the reservoir to replace the ink as it is removed therefrom in the operation of the pen, and to provide for convenient filling of the ink reservoir.

Another object of the invention is to provide a construction and arrangement wherein the writing end portion of the pen-point member is movable laterally within and with respect to the surrounding nozzle portion of the pen, thereby varying the area of the ink channel or ink space at the sides of the pen-point member.

A further object of the invention is to provide a pen of the character described having a translucent nozzle portion for ascertaining when the supply of ink for writing purposes is getting low.

A still further object of the invention is to improve devices of the character described in sundry details hereinafter referred to and particularly pointed out in the appended claims.

One embodiment of the present invention is shown for illustrative purposes in the accompanying drawing, in which:

Fig. 1 is an elevational view, partly in section, of a pen embodying features of the present invention;

Fig. 2 is an enlarged longitudinal sectional elevational view taken substantially as indicated by the line 2—2 of Fig. 1, the central portion of Fig. 2 being broken away to permit of showing the structure on a considerably enlarged scale;

Fig. 3 is an enlarged transverse sectional elevational view through the structure adjacent the writing end of the pen, and taken on the line 3—3 of Fig. 2;

Fig. 4 is a transverse sectional elevational view taken on the line 4—4 of Fig. 2; and

Fig. 5 is a further enlarged fragmentary sectional elevational view through a portion of the writing end of the pen showing the pen-point member in its position with relation to the nozzle 10 when the writing point is in engagement with a writing surface.

The illustrative embodiment of the present invention, as shown in the drawing, comprises a body portion, indicated as a whole by the numeral 11, consisting of a hollow tubular barrel 12 having a bulb 13 formed of rubber or other suitable flexible and resilient material positioned in one end of the barrel 12, and a nozzle, indicated as a whole by the numeral 14, positioned in the opposite end thereof, the said nozzle being shown, in the present instance, as comprising a tapered portion 15 formed preferably of a suitable translucent material such, for example, as glass or the like, and having a tubular shell or sleeve 16 positioned therein and extending beyond the outer end thereof, the said barrel 12 and nozzle 14 providing a container or reservoir 17 for maintaining a supply of ink within the device for writing purposes.

Mounted within the body portion 11 and shown, in the present instance, as positioned within the open end portion of the bulb 13 is a holder 18 shown, in the present instance, as provided with a recess 19 and formed, preferably, of rubber or other suitable flexible and resilient material, said holder 18 having apertures 21 formed therein communicating with the ink reservoir 17 and with the interior of the bulb 13.

Mounted in the holder 18, preferably adjacent the central portion thereof and adjacent the recess 19, is a pen-point member, indicated as a whole by the numeral 22, the member 22 being shown, in the present instance, as secured against longitudinal movement with respect to the holder 18 by means of annular shoulders 23 formed on the member 22 at opposite sides of the holder 18.

The member 22, as shown in the drawing, is adapted to extend through the shell or sleeve 16 of the nozzle 14 in spaced relation with respect thereto to provide an ink channel 24 communicating with the reservoir 17, the member 22 being adapted to extend beyond the discharge end of the shell 16 and ink channel 24 to provide a writing end 25 shown, in the present instance, 55

as provided with a flared or annular flange portion 26 adapted to engage a writing surface as shown by the line 27 in Fig. 5, where it will be apparent that the writing end 25 of the pen-point member 22 extends beyond the end of the sleeve 16 of the nozzle 14 and the discharge end of the ink channel 24, and it will be apparent also that a line, such as the plane of a writing surface, as 27 for example, touching the extreme outer edges 10 or points of contact of the sleeve 16 and writing end 25 is offset outwardly from the inner edge 16a of the sleeve 16 in a manner to maintain said inner edge of the sleeve 16 of the nozzle out of engagement with the writing surface when the pen is in writing position with respect thereto, thereby protecting the inner edge 16a of the nozzle against scooping up dust, dirt, paper fibers and the like, which would tend to clog the ink 15 passage 24 and seriously interfere with the efficient operation of the pen.

It will be noted also by reference, particularly, to Fig. 5 that by reason of the mounting of the pen-point member 22 in the resilient holder 18, the outer, free or writing end 25 of the member 22, when in engagement with a writing surface, may be moved laterally with respect to the sleeve 16 of the nozzle 14 in a manner to increase the distance between the inner surface of the sleeve 16 and the outer surface of the member 22 at 20 one side thereof, thereby enlarging the portion of the ink channel 24 adjacent the underside of the member 22 and permitting a free flow of the ink therethrough during the writing operation, and it will be noted also that when pressure on 25 the writing end 25 of the member 22 is relieved, the resiliency of the holder 18 will cause the member 22 to assume a substantially central position with respect to the sleeve 16, as shown in Fig. 2, in a manner to retain the ink against accidental 30 discharge from the reservoir through the ink channel 24.

The pen-point member 22 is shown, in the present instance, as of substantially tubular form having a longitudinally disposed air vent and 45 filler opening 28 formed therein and extending therethrough to permit of the admission of air into the bulb 13 and the ink reservoir 17 to replace the ink removed therefrom during the operation of the pen, and providing also, an intake 50 passage through which ink may be drawn into the pen during the filling operation by manipulation of the bulb 13, the ink during the filling operation being discharged from the upper or inner end of the member 22 into the lower end 55 of the bulb 13, from which it may pass through the apertures 21 into the reservoir 17.

For protecting the bulb 13 against accidental compression when the pen is in use, a cap or cover 29 may be screw threaded or otherwise secured to the upper end of the barrel 12 as clearly shown in Fig. 2.

It will be apparent that by the use of a translucent material in the construction of the tapered portion 15 of the nozzle 14, the user may ascertain when the supply of ink in the reservoir is getting low so that the pen may be refilled before the supply of ink is completely exhausted.

It will be observed from the foregoing description that the present invention provides a novel 70 construction and arrangement whereby the tip of the nozzle portion 16 of the pen is protected against scooping up dust, dirt and paper fibers or the like which would tend to clog the ink passage 24, and that by reason of the structure and arrangement shown and described, the present

invention provides a self-contained mechanical 5 filler by which the reservoir may be filled without resorting to the old method now employed in filling pens of the stylographic type.

It will be observed also that the present invention provides the novel means for venting the ink 10 reservoir and that by reason of the novel mounting of the pen-point member, the effective area of the ink channel may be controlled to insure a proper flow of ink therethrough.

Obviously, the present invention is not limited 15 to the precise construction and arrangement shown and described as the same may be variously modified. Moreover, all of the features of the invention need not be used conjointly as the 20 same may be used to advantage in variously different combinations and subcombinations.

What I claim as new and desire to secure by Letters Patent is:

1. In a fountain pen having a body portion 20 comprising a hollow barrel and nozzle to provide an ink reservoir in said body portion, the combination of a pen-point member fulcrumed adjacent its inner end in said body portion and extending through said nozzle in spaced relation thereto to provide an ink channel communicating with said reservoir, said point member having a writing end extending beyond the discharge end of said nozzle and having a laterally extending annular flange formed thereon 25 engageable with a writing surface for maintaining the inner edge of said nozzle out of engagement with said surface.

2. In a fountain pen having a body portion comprising a hollow barrel and nozzle to provide an ink reservoir in said body portion, the combination of a pen-point member fulcrumed adjacent its inner end in said body portion and extending through said nozzle in spaced relation thereto to provide an ink channel communicating 30 with said reservoir, said point member having a writing end movable laterally with respect to said nozzle and extending beyond the discharge end thereof, said writing end having a laterally extending annular flange formed thereon 35 engageable with a writing surface for maintaining the inner edge of said nozzle out of engagement with said surface.

3. In a fountain pen having a body portion comprising a hollow barrel and nozzle to provide an ink reservoir in said body portion, the combination of a resilient holder mounted in said body portion, a pen point member fulcrumed adjacent its inner end in said holder and extending through said nozzle in spaced relation thereto to provide an ink channel communicating 40 with said reservoir, said point member having a writing end movable laterally with respect to said nozzle and extending beyond the discharge end thereof, said writing end having a laterally extending annular flange formed thereon 45 engageable with a writing surface for maintaining the inner edge of said nozzle out of engagement with said surface.

4. In a fountain pen having a body portion 50 comprising a hollow barrel open at its ends and a tubular nozzle mounted in one end thereof to provide an ink reservoir in said body portion, the combination of an elongated hollow pen-point member fulcrumed in said body portion 55 and communicating with said ink reservoir for admitting air thereto, said point member extending through said nozzle in spaced relation thereto to provide an ink channel communicating with said reservoir, said point member hav- 60

ing a writing end movable laterally with respect to said nozzle and extending beyond the end thereof and engageable with a writing surface for maintaining the inner edge of said nozzle 5 out of engagement with said surface.

5. In a fountain pen having a body portion comprising a hollow barrel open at its ends and a tubular nozzle mounted in one end thereof to provide an ink reservoir in said body portion, 10 the combination of an elongated hollow tubular pen-point member fulcrumed adjacent its inner end in said body portion and communicating with said ink reservoir for admitting ink and air thereto, said point member extending 15 through said nozzle in spaced relation thereto to provide an ink channel communicating with said reservoir, said point member having a writing end movable laterally with respect to said nozzle and extending beyond the end thereof, 20 said writing end having a laterally extending annular flange formed thereon engageable with a writing surface for maintaining the inner edge of said nozzle out of engagement with said surface.

25. 6. In a fountain pen having a body portion comprising a hollow barrel and nozzle to provide an ink reservoir in said body portion, the combination of a hollow bulb of resilient material mounted on one end of said barrel and communicating with said reservoir, an elongated hollow tubular pen-point member fulcrumed in said body portion and communicating with the interior of said bulb and reservoir, said point member extending through said nozzle in spaced 30 relation thereto to provide an ink channel communicating with said reservoir and having a writing end movable laterally with respect to said nozzle and extending beyond the end thereof, said writing end being adapted to engage a 35 writing surface for maintaining the inner edge of said nozzle out of engagement with said surface.

7. In a fountain pen having a body portion comprising a hollow open ended barrel and a tubular nozzle mounted at one end thereof to provide an ink reservoir in said body portion, the combination of a hollow bulb of resilient material mounted on one end of said barrel, a resilient holder mounted in said body portion 45 and having apertures formed therein communicating with said reservoir and the interior of said bulb, an elongated hollow tubular pen-point member fulcrumed in said holder and communicating with the interior of said bulb, said point member extending through said nozzle in spaced 50 relation thereto to provide an ink channel communicating with said reservoir and having a writing end movable laterally with respect to said nozzle and extending beyond the end thereof, said writing end having a laterally extending 55 annular flange formed thereon engageable with a writing surface for maintaining the inner edge of said nozzle out of engagement with said surface.

60. 8. In a fountain pen having a body portion comprising a hollow open ended barrel and a tubular nozzle mounted at one end thereof to provide an ink reservoir in said body portion, the combination of a hollow bulb of resilient material mounted on one end of said barrel, a resilient holder having a recess formed therein adjacent the central portion thereof mounted in 65 said body portion, said holder having apertures formed therein communicating with said reservoir and the interior of said bulb, an elongated 70

hollow tubular pen-point member fulcrumed in said holder adjacent said recess and communicating with the interior of the bulb, said point member extending through said nozzle in spaced relation thereto to provide an ink channel communicating with said reservoir and having a writing end movable laterally with respect to said nozzle and extending beyond the end thereof, said writing end having a laterally extending annular flange formed thereon engageable with a writing surface for maintaining the inner edge of said nozzle out of engagement with said surface. 5

9. In a fountain pen having a body portion comprising a hollow open-ended barrel and a tubular translucent nozzle mounted in one end thereof to provide an ink reservoir in said body portion, the combination of a hollow bulb of resilient material mounted on one end of said barrel, a resilient holder mounted in fixed relation with respect to said body portion and having apertures communicating with said reservoir and the interior of said bulb, an elongated pen-point member mounted in and extending through said holder and having a filler and vent opening extending longitudinally of the point member from end to end thereof and communicating with the interior of said bulb, means adjacent one end portion of the point member cooperating with said holder for securing said member against longitudinal displacement with respect to the holder, the opposite end portion of said point member extending through said nozzle in spaced relation thereto to provide an ink channel communicating with said reservoir, said point member having a writing end movable laterally with respect to said nozzle and extending beyond the end thereof, said writing end having a laterally extending annular flange formed thereon engageable with a writing surface for maintaining the inner edge of said nozzle out of engagement with said surface. 20 25 30 35 40

10. In a fountain pen having a body portion comprising a hollow barrel and nozzle to provide an ink reservoir in said body portion, the combination of a pen point member positioned in said body portion and extending through said nozzle in spaced relation thereto to provide an ink channel communicating with said reservoir, said point member having a writing end extending beyond the discharge end of said nozzle, and a laterally extending flange portion formed on the outer end of said member adjacent the discharge end of said ink channel and adapted to overlie a portion of the end of said nozzle. 45 50 55

11. In a fountain pen having a body portion comprising a hollow barrel and nozzle providing an ink reservoir in said body portion, the combination of a tubular member positioned in said body portion and communicating with said reservoir, said tubular member extending through said nozzle in spaced relation thereto to provide an ink channel communicating with said reservoir. 60

12. In a fountain pen having a body portion comprising a hollow barrel and tubular nozzle to provide an ink reservoir in said body portion, the combination of a tubular member positioned in said body member and communicating with said reservoir to provide a filler and vent opening therefor, said tubular member extending through the opening in said nozzle in spaced relation thereto to provide an ink channel communicating with said reservoir. 65 70 75
